UNITED STATES PATENT OFFICE.

HARRY C. LINDOL, OF PROVIDENCE, RHODE ISLAND.

DESIGN FOR A BRACELET.

SPECIFICATION forming part of Design No. 17,070, dated January 18, 1887.

Application filed December 16, 1886. Serial No. 221,806. Term of patent 14 years.

To all whom it may concern:

Be it known that I, HARRY C. LINDOL, a citizen of the United States, residing at Providence, in the county of Providence and State 5 of Rhode Island, have invented and produced a new and original Design for Bracelets, of which the following is a specification, reference being had to the accompanying drawings, forming part of said specification.

Figure 1 represents the bracelet open. Fig. 2 represents it closed. Fig. 3 represents it in side view.

My invention relates to bracelets of that class in which the ends overlap and are provided with terminal knobs or enlarged ornaments; and it consists in the design of a bracelet having a terminal knob or enlargement on the end of each arm of the bracelet, and also having on each arm, at a little distance from 15 the said terminal knobs or enlargements, a ball or sphere set upon the said arm on its outer arc, as clearly shown in Fig. 2.

The leading feature of my design consists in these connecting spherical or globular projections on the outer arc of the arms and a short 25 distance from the terminal knobs.

Referring to the accompanying drawings, B 30 represent the terminal knobs or enlargements, and C C the intermediate balls, which are preferably a little smaller than the terminal knobs.

I claim as my invention—

The design for a bracelet herein shown and described, the same consisting of the bracelet arm or band provided with terminal knobs or 35 ornaments and the intermediate balls, C C, as set forth.

In testimony whereof I have signed my name to this specification in the presence of two subscribing witnesses.

HARRY C. LINDOL.
